UNITED STATES PATENT OFFICE.

JOSEPH R. MULRONEY, OF FORT DODGE, IOWA, ASSIGNOR TO MULRONEY MANUFACTURING COMPANY, OF FORT DODGE, IOWA, A CORPORATION OF IOWA.

POCKET CONSTRUCTION.

Application filed May 18, 1925. Serial No. 31,135.

To all whom it may concern:

Be it known that I, JOSEPH R. MULRONEY, a citizen of the United States, residing at Fort Dodge, in the county of Webster and State of Iowa, have invented a certain new and useful Pocket Construction, of which the following is a specification.

The object of my invention is to provide a pocket construction especially applicable for overalls, or work garments, wherein tools and the like are ordinarily kept in the pockets.

More particularly, it is my object to provide an elastic member which forms a part of the pocket itself, which elastic member is fastened to the back side of the pocket or material of the garment at spaced points so as to permit the elastic member to give or stretch, being only restricted by the elasticity of the member itself between the points where it is fastened to the garment or back side of the pocket.

Still a further object is to provide an elastic member in the front piece of the pocket, which elastic member is fastened between its ends to the back piece of the pocket or garment, which fastenings terminate short of the top and the bottom of the elastic member itself so as to permit greater elasticity of the elastic member between the place where it is fastened to the front piece and where it is fastened to the back piece so as to permit a pair of pliers or other article to be easily slipped into position and received by the elastic member for retaining the pliers or other implement against accidental displacement.

Reference is here made to my copending application for a pocket construction, filed May 18, 1925, Serial No. 31,136.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a front view of a portion of a garment with my improved pocket construction shown thereon.

Figure 2 is a central, vertical, sectional view taken on line 2—2 of Figure 1.

Figure 3 is a horizontal, sectional view taken on line 3—3 of Figure 1 through the 55 elastic member.

Figure 4 is a front, plan view of a pocket construction, which is concealed or covered by the front of the garment itself; and

Figure 5 is a vertical, sectional view taken 60 on line 5—5 of Figure 4.

In the accompanying drawings, I have used the reference numeral 10 to indicate a portion of a garment upon which is adapted to be sewed or otherwise fastened, a front 65 pocket forming piece 11.

The portion of the garment 10, which is covered up by the front pocket piece 11 may be properly called the back piece of the 70 pocket.

The front and back pieces are stitched together along their two side edges and their bottom so as to form a pocket closed on three sides and open on its top.

The front piece 11, as shown in Figure 1 75 of the drawings, is formed of two small sections or pieces 11^a and 11^b connected together by an elastic member 12. The elastic member 12 is stitched or otherwise secured at its upper edge to the lower edge of the 80 piece 11^a and secured at its bottom edge to the top edge of the piece 11^b.

The elastic member 12 is substantially the same width as the pieces 11^a and 11^b, and is stitched at its side edges to the back piece 85 of the garment 10.

The elastic member, as it appears in Figure 1 of the drawings, is not covered up by any of the cloth of the front piece 11, thereby permitting free unrestricted elasticity of the 90 member 12.

The elastic member 12 is further fastened to the back piece 10 by stitches 13, although clips or staples of any suitable kind may be used, which will serve the purpose herein 95 contemplated, as a fastener.

It will be particularly noted, that the stitches or fastenings 13, preferably terminate short of the top and bottom edges of the elastic member 12, and this serves a very 100 important function which I will now describe in detail.

It is very desirable to permit the elastic member between the points of fastening to the front piece 11, and the back piece 10, to be free to expand its maximum without 105

any restrictions, except as to its elasticity.

The terminating of the fastenings 13 short of the top and bottom edges of the member 12 prevents the cloth of the pieces 11^a and 11^b from restricting or retarding the elasticity of the member 12.

It may be here mentioned that if the fastenings 13 extended clear to the top and bottom edges of the elastic member 12, then 10 the cloth of the pieces 11^a and 11^b would prevent stretching of the member 12, at the point where it was fastened to the pieces 11^a and 11^b.

In the present construction, as shown in 15 Figure 1 of the drawings, a pair of pliers or the like may be inserted between the outer edges of the pocket and the fastenings 13, and may be forced into position the elastic member stretching to accommodate any pair 20 of pliers or other such implement. The particular fastening 13 and the elastic member 12 affords the "stretch" necessary to hold an article in position against accidental falling out.

25 In Figures 4 and 5 of the drawings, I have shown the garment, referred to by the reference numeral 10, as formed with a slit 15 to the edges of which may be secured a pocket of the concealed type formed of a 30 front piece 11 and a back piece 14. Either type of pocket here shown can be easily and cheaply manufactured and marketed.

The front piece 11 is made very much like the front piece 11 shown in Figure 1 of the drawings, that is, it consists of two pieces 35 11^a and 11^b arranged with an elastic member 12 therebetween.

The elastic member 12 is secured between its side edges to the back piece 14 by the 40 stitches or fastenings 13.

The operation and functions of the pocket, as shown in Figure 4 of the drawings, is exactly like the one shown in Figure 1 of the drawings.

45 The pocket in the case of Figure 4 is completely concealed by the garment 14 itself, although the elasticity of the member 12 is unrestricted because there is no fastening of it directly to the garment 10 itself.

50 The principal feature of my pocket construction resides in the arrangement of an elastic member that is free to expand without any restriction.

I am aware of the fact that elastic mem- 55 bers have been used in pockets, and in such

cases has always been used with a covering of cloth or within the pocket itself so that the cloth actually restricts the free elasticity of the elastic member itself, and this is a disadvantage in pocket construction which I 60 am overcoming by my construction.

Some changes may be made in the construction, and arrangement of the various parts of my invention, without departing from the real spirit and purpose of my invention, and it is my intention to cover by my claims, any modified forms of structure or use of mechanical equivalents, which may be reasonably included within their scope.

I claim as my invention:

1. A pocket construction for garments and the like comprising a front and back piece of textile material stitched together along two sides and the bottom edge, one of said pieces having an opening therein, an elastic member inserted in said opening, a fastening between said elastic member and the other piece of the pocket, said fastening terminating short of the upper edge of the elastic member for permitting unrestricted elasticity of the upper portion of said elastic member above the fastening. 70 75

2. A pocket construction for garments and the like comprising a front and back piece of textile material stitched together along two sides and the bottom edge, one of said pieces having an opening therein, an elastic member inserted in said opening, a fastening between said elastic member and the other piece of the pocket, said fastening terminating short of the upper and lower edges of the elastic member for permitting unrestricted elasticity of the upper and lower portions of said elastic member above the fastening. 85 90

3. A pocket construction for garments and the like comprising a front and back piece of textile material stitched together along two sides and the bottom edge, one of said pieces having an opening therein, an elastic member inserted in said opening, a plurality of spaced fastenings between said elastic member and the other piece of the pocket, said fastenings terminating short of the upper edge of the elastic member for permitting unrestricted elasticity of the upper portion of the elastic member above the fastenings. 100 105

Des Moines, Iowa May 12, 1925.

JOSEPH R. MULRONEY.
